UNITED STATES PATENT OFFICE.

OSCAR A. BÖHM, OF NEW YORK, N. Y.

METHOD OF MANUFACTURING TIPLESS MINIATURE INCANDESCENT SEARCH-LAMPS.

No. 825,103.

Specification of Letters Patent.

Patented July 3, 1906.

Application filed May 6, 1904. Serial No. 206,606.

To all whom it may concern:

Be it known that I, OSCAR A. BÖHM, a citizen of the United States of America, and a resident of New York, county and State of New York, have invented certain new and useful Improvements in Methods of Manufacturing Tipless Miniature Incandescent Search-Lamps, of which the following is a specification.

10 This invention relates to a novel method of manufacturing tipless miniature incandescent electric lamps, and pertains particularly to that type of incandescent electric lamps known as "miniature" search-lamps. 15 My lamp does not possess the usual tip at the top of the globe or vacuum-chamber, and therefore does not cast an undesirable shadow. As the name indicates, miniature search-lamps are very small and when provided with a 20 tip at the top of the globe, as in former constructions, the passage of light is obstructed. Owing to the small size of miniature lamps, it is impossible to insert an exhaust-tube inside of the hollow stem, because there is no room 25 for same, besides the stem is too short for this purpose. Likewise it is impracticable to blow an exhaust-tube directly to the lower portion or neck of the globe or vacuum-chamber. This will add prohibitive cost to the 30 price of the lamp, because skilled labor is required for attaching an exhaust-tube to the lower part of the neck, owing to the small size of same and close proximity of the leading-in wires. Furthermore, less lamps can be made 35 per day. Likewise the cost of producing such small lamps with an exhaust-tube at the bottom end is so great as to render it impossible to compete in the market. In the latter instance the leading-in wires must pass angularly through the side walls of the neck, which 40 is undesirable for miniature lamps.

It is a special feature of my novel miniature search-lamp that the tip is neither at the top of the globe nor on or at the end of the 45 neck. Notwithstanding, my lamp does not cost any more than the ordinary miniature search-lamp, which latter has the exhaust-tip at the top of the globe. This is due to the novel method of making same, and in addition hereto my lamp does not need to be tubulated, as will be described farther down.

The application of such incandescent electric miniature search-lamps is manifold. They are preferably used in connection with 55 dry batteries, for instance, in the top portion of walking-canies, in the so-called "ever-

ready flash-lights," as inspectors' lamps, in coal-mines, as bicycle-lamps, in powder factories, and wherever explosive substances are manufactured. Further, they are used 60 on the guns of war vessels when adjusting the gun at night for firing. Likewise such lamps are employed by plumbers in cellars, physicians at night in the residences of patients, hunters, railroad trackmen, switchmen, operators, brakemen, oilmen, policemen, detectives, machinists, engineers, and for all purposes where a light is instantly required. A large number are also used in electric novelties, such as scarf-pins, &c. 65

The invention is illustrated in the accompanying drawings, in which—

70 Figure 1 represents in side elevation the top portion of a miniature search-light. Fig. 2 is a vertical section of same, showing the 75 lamp in elevation. Fig. 3 represents a glass tube having a handle, neck, and contraction formed thereon. Fig. 4 illustrates the glass tube having neck, contraction, and bulb formed thereon. Fig. 5 shows the bulb and 80 neck with wires and carbon sealed therein ready for exhaustion, and Fig. 6 shows the completed lamp sealed off.

Similar letters of reference denote like 85 parts in all the figures.

In the drawings, *a* represents a tubular socket made of metal, in which the lamp *b* with base *c* is secured. A tubular holder *d* fits closely into the socket *a*. In the top portion of said tubular holder *d* there is mounted 90 a lens *e*. (See Figs. 1 and 2.) It is plainly seen that the light emitted by the incandescent conductor within the lamp must pass the lens *e*, while the light radiated on the sides of the incandescent lamp will strike the metal 95 walls of the lens-holder *d*. Therefore the lamp has no tip at the top of the globe or vacuum-chamber *l*. On the contrary, the tip *m* in my novel miniature search-lamp is located on one side of the globe or vacuum-chamber, as shown in Figs. 2, 5, and 6. From 100 Fig. 1 it is apparent that the light emitted by the lamp is in no way obstructed and passes through the lens free from any shadow.

105 In manufacturing my lamp I substantially proceed as follows: A glass tube *f* is drawn out to a point *g*, which forms the handle. Then a contraction *h* is formed thereon, as shown in Fig. 3. So far there is practically no difference between this and other lamps. 110 Now the portion *f'* of the glass tube is heated, and while doing this the fusing glass is turned

in the flame and twisted in such a manner that the large quantity of the fused glass is on one side. Simultaneously the portion *f* of the tube with the contraction is gradually moved sidewise. After the portion *f* of the glass tube has been heated in the described manner the bulb is blown, and while blowing same the portion *f* with the contraction *h* is further moved sidewise and upward until it is 5 in the position indicated in Fig. 4. The tube *f* constitutes now the exhaust-tube. It must be observed that according to the described method a lamp bulb or globe is produced which has no tip at the top of said globe or 10 bulb. Still it possesses the exhaust-tube away from the top of the globe, although it has not been tubulated. When the bulb or globe is thus finished, the leading-in wires *i*, with supporting-braces *j* and carbon *k*, are 15 now sealed into the globe in the usual manner. It is of course understood that the wires, with supporting-brace and carbon, have been separately prepared. Now the lamp is 20 ready for exhaustion and may be applied to the air-pump for the purpose of creating a vacuum therein. After the vacuum has 25 been created the lamp is sealed in the usual manner and is now ready to receive the base *c* and to be inserted in the socket *a*. 30 The method of manufacturing this lamp, and particularly the novel method of blowing the bulb in such a manner that the contraction *h* and the exhaust-tube *f* are in the 35 position shown in Figs. 4 and 5, insures a quick production of the lamp, and therefore the lamp will not cost any more than the old-style lamp having the tip on the top. The

novel lamp, however, presents the advantage of being a tipless lamp for the purposes intended and does not share the deficiencies 40 of the former lamp, which has the tip at the top of the globe. Furthermore, for blowing globes with the contraction and exhaust tube on the side of same the raw material—*i. e.*, the glass tubes—need not be carefully selected as to regular thickness of the side walls. 45

Having thus described my invention, I claim as new and desire to secure by Letters Patent—

1. The method of manufacturing globular 50 vacuum-chambers for tipless incandescent miniature search-lamps consisting in blowing up the globe or bulb while the exhaust-tube with contraction is turned and twisted sidewise and upward so as to get the large quantity of glass on one side whereby a globe is 55 formed during one operation which has a smooth top and the exhaust-tube on the side.

2. The method of producing tipless incandescent miniature electric search-lamps consisting in blowing up the globe or bulb while the exhaust-tube with contraction is turned and twisted sidewise and upward so as to get the large quantity of glass on one side whereby a globe is formed during one operation 60 which has a smooth top and the exhaust on the side, inserting the wires with carbon, exhausting the lamp, and sealing it off. 65

Signed at New York, N. Y., this 5th day of May, 1904.

OSCAR A. BÖHM.
